UNITED STATES PATENT OFFICE.

ADOLF CLEMM, OF MANNHEIM, GERMANY.

PROCESS OF TREATING BARIUM CHLORID AND STRONTIUM CHLORID FOR PRODUCING CHLORIN AND HYDROXID OF THE SAID METALS.

973,171.

Specification of Letters Patent. Patented Oct. 18, 1910.

No Drawing.

Application filed March 11, 1910. Serial No. 548,672.

To all whom it may concern:

Be it known that I, ADOLF CLEMM, a subject of the German Emperor, and resident at Mannheim, Germany, have invented certain new and useful Improvements in Processes of Treating Barium Chlorid and Strontium Chlorid for Producing Chlorin and Hydroxids of the Said Metals, of which the following is a specification.

10 My invention relates to improvements in a process of treating barium chlorid and strontium chlorid for producing chlorin and hydroxids of the said metals.

For making hydroxids of alkaline earths numerous processes have been suggested and many patents have been granted in which such processes are described, and many of these processes relate to producing barium hydroxid. Generally speaking two different ways have been suggested for producing the said hydroxids. One of these ways consists in mixing the carbonates, (which may be either natural carbonates or carbonates which are obtained by reducing sulfates by means of coal and treating the product with carbonic acid), with coal and heating the same to intense red heat, whereupon the hydroxid is obtained by washing the product with water. A second way consists in reducing the sulfates by heating the same with coal and transforming the sulfid thus obtained into a metallic sulfid and hydroxid by means of a metallic oxid. Furthermore, efforts have been made to produce hydroxid by heating sulfate with coal and calcium carbonate and lixiviating the hydroxid thus obtained.

My invention consists in producing the aforesaid hydroxids from their chlorids, by decomposing the same by electrolysis into gaseous chlorin and into hydroxid, the latter being produced in a special way.

By my experiments I have discovered that when the electrolytic decomposition is carried to that point only where the chlorid solution is nearly saturated with the hydroxid (which is for example the case when electrolyzing barium chlorid at a temperature of from 20 to 25 degrees centigrade with an amount of from 35 to 40 grams of barium hydroxid within one liter) and when the solution thus obtained is intensely cooled, the larger crystallizing part of the hydroxid contained in the solution can

easily be obtained in a pure state by centrifugal action and washing. During the electrolysis gaseous chlorin is simultaneously formed which is collected and used for any desired purpose. The liquid resulting from the said operation contains slight quantities of hydroxid which is turned back with the chlorid into the process, or it can be deposited in the form of pure carbonate by means of carbonic acid.

The process may be termed a process of a partial electrolysis, and in the first stage of the said process substantially equivalent amounts of hydroxid and chlorin are produced. The amounts of chlorids of alkaline earths which were not decomposed and the remaining small quantity of hydroxid contained therein are turned back into the process, provided the said hydroxid is not precipitated before the solution, from which the hydroxid and the chlorin were separated, has been brought to its original concentration by evaporation or by dissolving therein solid chlorid.

As the solubility of the hydroxid of the two alkaline earths is considerably larger at high temperatures than at low temperatures, the cathode liquid is preferably heated during the electrolysis, as is done in the electrolysis of the alkalies, because in this case the decomposition can be carried somewhat farther (in the example of the barium compound stated above, at a temperature of from 50 to 60 degrees centigrade to from 60 to 70 grams of barium hydroxid in one liter).

Notwithstanding the partial decomposition occurring in the process, the latter can be made a continuous process of producing chlorin and hydroxid, if at one side of the baths the chlorid solution which is electrolyzed in the critical point is slowly or at intervals withdrawn, while at the opposite side of the baths a corresponding amount of the solution of the chlorid is admitted.

For the purpose of obtaining gaseous chlorin and hydroxid of barium or strontium the process described may be modified by making use of chlorids of alkalies and adding to the electrolyte so much chlorid of alkaline earth, that from the alkali hydroxid formed by the partial electrolysis described above alkali chlorid is again formed and the

corresponding hydroxid of alkaline earth is produced which can be obtained from the chlorid solution in the same way as described above by crystallization etc.

5. The process may be carried on in any well known apparatus and even in a simple cell.

I claim:

1. The herein described process of producing chlorin and an hydroxid of an alkaline earth metal which comprises subjecting a solution of a chlorid of an alkaline earth metal to electrolysis until the chlorid solution is nearly saturated with the hydroxid,

10 2. The herein described process of producing chlorin and an hydroxid of an alkaline earth metal which comprises subjecting a solution of a chlorid of an alkaline earth metal to electrolysis until the chlorid solution is nearly saturated with the hydroxid,

and gradually withdrawing the solution 20 which is saturated with the hydroxid.

3. The herein described process of treating an alkaline earth metal chlorid for producing chlorin and the corresponding hydroxid by electrolysis, which comprises 25 subjecting the solution of such chlorid to a partial electrolysis until the solution of the chlorid is nearly saturated with the corresponding hydroxid, withdrawing the solution, and cooling the withdrawn solution 30 and thereby crystallizing the hydroxid.

In testimony whereof I have signed my name to this specification in the presence of two subscribing witnesses.

ADOLF CLEMM.
